[57] **ABSTRACT**

A stained glass in concrete art assembly including a plastic panel having glass texture simulating surface projections therein which are rendered visible when the back surface of the projections are painted with a coloring medium and which contribute to providing a simulated appearance of authentic stained glass to the plastic panel. The front side of the plastic panel is painted with sand paint thereby providing a simulated appearance of concrete.

FIG. 2

FIG. 4

SIMULATED STAINED GLASS IN CONCRETE ART ASSEMBLY

The present invention relates generally to art craft kits, and more particularly to a kit or assembly in which the resulting product simulates authentic stained glass in concrete and yet consists primarily of plastic.

Simulated glass art work is known which includes a transparent sheet having a series of embossed regions which are shaped to simulate individual glass. This type of art work has been fabricated through coloring the embossed regions or projections by painting the rear surfaces thereof. The painted plastic panel is then mounted on a colored backing sheet in order to provide a simulated mortar-type background. However, these prior attempts to provide a simulated stained glass art assembly and, in particular, to provide a simulated stained glass art assembly which is realistic in its simulation, has not been completely successful.

Accordingly, an object of the present invention is to provide an art assembly which provides an authentic simulation of stained glass and, in particular, which provides a realistic stained glass in concrete presentation.

A further object of the present invention is to provide a simulated stained glass in concrete art assembly which not only provides a product of noteworthy appearance, but which also requires a degree of participating activity by the user that contributes favorably to the play value of the art assembly.

A simulated stained glass in concrete art assembly demonstrating objects and advantages of the present invention includes a transparent plastic panel having surface projections therein. Advantageously, the plastic panel is formed with an irregular surface in order to increase the antique and textured nature of the art assembly. The rear surface of the projections are painted with a coloring medium in order to provide a simulation of stained glass. The front of the plastic panel, defined between the projections, is adapted to be painted with sand paint in order to provide a simulation of concrete. Together, this provides a simulated stained glass in concrete art assembly which is realistic in appearance.

The above brief description, as well as other objects, features and advantages of the present invention, will be more fully appreciated by reference to the following detailed description of a presently preferred, but nonetheless illustrative embodiment in accordance with the present invention, when taken in conjunction with the accompanying drawings, wherein:

FIG. 1 is a front perspective view of a panel used in the stained glass in concrete art assembly according to the present invention;

FIG. 2 is an enlarged, fragmentary sectional view of the transparent panel showing the application of a coloring medium to the rear surface of the projections;

FIG. 3 is a front, elevation view of the simulated stained glass in concrete art assembly of the present invention; and,

FIG. 4 is an enlarged, fragmentary sectional view, taken substantially along the line 4-4 of FIG. 3, and looking in the direction of the arrows.

Referring now specifically to the drawings, there is shown a simulated stained glass in concrete art assembly according to the present invention which is generally designated by the reference numeral 10. Art as-

sembly 10 includes a transparent plastic panel, generally designated 12, which is adapted to be mounted in a mounting frame, generally designated 14, for example, by the utilization of tacks or other fastening elements 16.

Transparent plastic panel 12 is adapted to be formed with a background surface 18 which, as will be explained hereinafter, is adapted to be painted with sand paint thereby providing a simulated concrete background for the art assembly.

Plastic panel 12 is also formed with a plurality of projections 20 which extend generally upwardly from background surface 18. As indicated in FIG. 1, projections 20 are adapted to be arranged in an artistic configuration and, as will be explained hereinafter, the projections are adapted to simulate stained glass.

Referring to FIG. 2, projections 20 are formed with sidewalls 20a which extend upwardly from background surface 18 at a slight angle. The sidewalls 20a of projections 20 terminate at a substantially flat top or front face 20b. The front faces 20b of projections 20 are all disposed in substantially a common plane, parallel to the plane of the background surface 18.

Advantageously, transparent plastic panel 12, which forms both background surface 18 and projections 20, is of an uneven cross-section or of an irregular surface thereby providing a textured or antique appearance for the stained glass in concrete art assembly. The transparent plastic panel may be formed by techniques well known in the art.

In order for projections 20 to provide a stained glass simulation for art assembly 10, a color medium is applied to the projections. Specifically, a color medium, such as paint 22, is applied by a brush 24 or similar instrument to the rear surface 20c of front faces 20b of the projections. Advantageously, in order to easily apply the colored medium 22 to the projections, the transparent plastic panel 12 may be turned upside-down (as indicated in FIG. 2) allowing the paint or color medium to be applied to the well which is then formed by the front faces 20b and the sidewalls 20a of the projections.

In order to provide the concrete simulation for art assembly 10, sand paint 26 is applied to the background surface 18 of plastic panel 12. Referring to FIG. 4, the sand paint 26 is applied to the top or front surface 18a of background surface 18. It has been found that the use of sand paint, which may be painted on the top face of background surface 18 by a brush 24 or similar instrument, provides a very realistic simulation of concrete. It has been found that this simulation of concrete is more realistic and superior to other art assemblies which merely utilize a cardboard or similar backing which is mounted behind the plastic panel.

As indicated hereinbefore, the irregular surface or cross-section of the plastic panel provides a realistic antique or textured simulation, both for the stained glass, provided on projections 20, and for the concrete, provided on background surface 18. Further, the realistic simulation of stained glass in concrete art assembly 10 is provided by the somewhat sloping nature of sidewalls 20a of the projections 20 which slope in a slightly converging angle from background surface 18 toward the front faces 20b of the projections. This provides a vivid three-dimensional effect allowing the simulated stained glass to "stand out" from the simulated concrete background.

From the foregoing, it should be readily appreciated that the stained glass in concrete art assembly 10 not only has an interesting decorative appearance but also provides considerable play value in the step by step procedure for forming and mounting the same. Obviously, numerous modifications are possible in light of the above disclosure. For example, the art assembly need not be mounted on a mounting or picture frame 14 but may be mounted in other ways. It is to be understood, therefore, that the described embodiment is merely illustrative of the teachings of the present invention and other modifications are possible within the principles of the invention.

What is claimed is:

1. A simulated stained glass in concrete art assembly comprising a transparent panel fabricated of plastic, the front face of said panel being substantially flat to provide a background surface disposed substantially in a single plane, said panel being formed with a plurality of projections each standing upwardly and outwardly from said background surface, each of said projections including sidewalls generally upstanding from said background surface and a front wall providing a front face spaced forwardly of and substantially parallel to said background surface, color medium deposited on the rear face of each of said front walls of said projec-

tions, and visible through the corresponding front faces of said projections, the shape of said projections and said color medium together providing an artistic simulated stained glass assembly standing forward of said background surface, sand paint on said front face of said panel covering substantially all of said background surface to provide a simulated concrete background for said arrangement, the placement of said sand paint on the front face of said panel directly providing a textured surface simulating a concrete surface, and said color medium deposited on said rear face of each of said front walls of said projections providing the simulation of stained glass when said color medium is viewed through the said transparent plastic panel.

2. The invention according to claim 1 wherein said panel is of a irregular cross-section thereby providing a textured simulation for said stained glass and concrete.

3. The invention according to claim 1 wherein said walls slope upwardly from said background surface at a slight angle with said sidewalls converging toward said front face.

4. The invention according to claim 3 wherein the front faces of said projections are all disposed in a common plane.
